UNITED STATES PATENT OFFICE.

JOSEPH E. LYNAM, OF SAN JOSE, CALIFORNIA.

BERRY-BOX MACHINE.

No. 862,085.

Specification of Letters Patent.

Patented July 30, 1907.

Application filed July 31, 1905. Serial No. 271,988.

To all whom it may concern:

Be it known that I, JOSEPH E. LYNAM, a citizen of the United States, residing in San Jose, in the county of Santa Clara and State of California, have invented new and useful Improvements in Berry-Box Machines, of which the following is a specification.

My invention relates to machines for making berry-boxes or baskets from strips of thin material as wood veneer, and has for its object to provide mechanism for receiving the strips of material separately for each box, and automatically arranging them in proper position and bending them into shape and securing the ends of the strips together to form them into a box, after which they are discharged.

With these and other objects in view my invention consists in the improved construction and novel arrangement of parts of such a machine as will be herein-after more particularly set forth.

The accompanying drawings illustrate the invention.

Figure 1 is a broken side-elevation of a machine embodying my invention. Fig. 2 is a broken top-plan view. Fig. 3 is a broken side-elevation, partly in section with some of the parts omitted. Fig. 4 is a sectional side-elevation. Fig. 5 is a plan-view of the top of one of the formers enlarged. Fig. 6 is a transverse sectional-view of a portion of the former-carrying wheel showing one of the formers. Fig. 7 is a front-view of the presser-head and folders. Figs. 8 and 9 are side and end-elevations respectively, of the wheel rotating mechanism.

In constructing a machine in accordance with my invention a suitable wheel 1 is mounted on a frame 2 and driven from any suitable source of power through a fly-wheel 3 and gearing 4. The wheel is preferably formed of two sides or disks 5 and 6 mounted on an axle 7. The periphery of the wheel is provided with a series of formers 8, preferably six in number, which are adapted to be consecutively brought under a presser-head 9.

The formers 8 are preferably constructed by securing sides or wings 10 to projections 11 on the periphery of the wheel, and arranging a movable bottom 12 between them. The wings are as long as the bottom of the box is wide, and the outer edges are such a distance apart that wings or folders 13 on the presser-head 9 will bend the material for the bottom of the box down over the wings when the presser-head descends. The bottom 14 of the presser-head is preferably in the form of a plate and is spring-pressed, as by providing it with a stem 15 which projects through the head and locating a spring 16 between the bottom and the head, as shown in Fig. 7. A shoulder, as a pin 17 through the stem above the head, holds the bottom 14 substantially even with the lower edges of the folders 13 so as to engage with the material and hold it against movement simultaneously

with the engagement therewith of the folders. The folders 13 are preferably, loosely secured to the head 9 so as to permit of a slight outward movement of their lower edges when they first engage with the material and thereby avoid an excessive strain by bending the material too abruptly. Springs 18 are arranged between the head of bolts 19 and the folders 13 to permit of the outward movement but which are strong enough to subsequently force the folders back into their former position and thereby cause the ends of the bottom to be properly bent over the sides of the wings 10. The spring 18 is strong enough to hold the bottom upon the former until after the folders 13 become disengaged therefrom when the presser-head 9 is raised to permit of the further operation of the machine in completing the formation of the box.

A flat flexible finger 20 projects beyond each side of the bottom 14 and has its end bent downward slightly so as to engage with the edges of the material and properly position it upon the folder before it is engaged by said bottom and the folders 13.

The bottom 12 of the former is mounted upon a stem 21 which is adapted to be reciprocated through two projections 22 which extend from one of the sides of the wheel toward the other. A finger or projection 23 extends through a slot 24 in one side of the wheel by means of which the bottom 12 may be moved downward and spring 25 returns the bottom to its normal position after it has been moved downward by the finger 23 to eject a completed box.

Pivottally mounted in the sides of the wheel at each side of the former is a shaft 26 on each end of which is rigidly secured a wing or folder 27 which is adapted to be swung in against the material for the sides of a box which has been deposited on notched stops 28 which project beyond the sides of the former and thereby bend the ends of said material across the ends of the bottom in position to be secured by stitchers in the ordinary manner. The wings at one end of the former are preferably wider than at the other so as to engage with the material at that side of the box and fold it in before the wings at the other end of the former bend in the ends of the material of that side. These shafts and wings are preferably actuated by means of a block 100 or head 29 which is loosely mounted upon the stem 21 and provided with a projection or finger 30 which projects through a slot 31 in the side of the wheel. Two links 32 are connected with the head 29 and with the arms 33 which are connected respectively with the shafts 26 and cause the wings 27 to be moved toward and from the former as the head 29 is reciprocated.

Reciprocally mounted in suitable bearings on the axle 7 at one side of the wheel is a frame 34 which is adapted to be moved back and forth by means of an L-shaped lever 35 and a cam 36 mounted on one of the shafts of the gearing 4. One of the arms of the lever is

preferably jointed as shown in Fig. 4 and the end-member is provided with an extension 38 which projects beyond the pivotal point 39 and is connected with the other arm of the lever by means of a spring 40. A set-screw 41 projects through the extension 38 and engages with the lever 35, preferably at about its pivotal point for adjusting the movable member of the lever so as to secure the operation of the frame 34 by the cam at the proper instant. One end of the frame 34 is adapted to 10 engage with the finger 30 to close the wings 27 upon the former and the other end with the finger 23 to eject a completed box when the frame is moved into its lowest position as shown in Fig. 4. As the wheel 1 continues its revolution after the downward movement 15 of the frame, the spring 25 returns the bottom 12 and the finger 23 to their normal position and the finger 30 engages with a stationary cam 43 at the side of the wheel which returns the head 29 to its normal position and thereby swings open the wings 27 for the reception 20 of material at the sides of the former.

The wheel is given an intermittent motion by means of a lever 44 at one side of the frame 2, one end of which is actuated by a cam 45 and the other end is provided with a link or push-rod 46 which is adapted 25 to engage with recesses 47 in a disk 48 mounted at one end of the axle 7. The push-rod 46 is preferably formed from two members which are connected at their upper ends by means of a cross-bar 49 which engages with the teeth of the disk 48 formed by the recesses 47. The cross-bar is held in engagement with the periphery of the disk at all times by means of a spring 50 which is connected with one of the members of the push-rod and with the lever 44. The disk is locked against movement by means of a pin 51 on a 30 V-shaped lever 52 which is adapted to be automatically drawn into recesses 53 in the disk 48 by means of a spring 54. The other end, 52^a of the lever 52 extends in the path of the cross-bar 49 as the latter is moved alternately up and down by the cam, while the cross-bar will engage the said projecting end 52^a of the lever 52 in the upward movement of the push-rods 46, and thereby throw the pin 51 out of the locking-recesses 53. The cross-bar 49 will slip over the end 52^a on the reverse movement of the cross-rods, without acting on 40 the lever 52. The recesses 47 are so arranged relatively to the formers 8 upon the wheel 1 that whenever the push-rod reaches the limit of its upward movement one of the formers will stand directly under the presser-head 9, as shown in Fig. 1.

50 After the material which is fed to the machine in any suitable manner has been folded upon one of the formers as above described the wheel is given a partial revolution which forces another former with its material under the presser-head 9 and also carries the preceding former with its folded material forward to the stitching mechanism 55 as shown in Fig. 1. As the stitching mechanism may be of any desired construction and forms no part of the present invention it is not necessary to describe it further than to say that the 55 stitchers are preferably arranged in duplicate on each side of the wheel so as to fasten the ends of the sides of the basket at two points as shown at 56 and thereby secure sufficient strength where the box is of such extreme width as shown in the drawings.

60 65 The plunger 57 and other mechanism of each stitcher

is actuated by means of an arm 58 mounted upon a rock-shaft 59 which is arranged vertically in the machine, one upon each side. The shafts 59 are actuated simultaneously by means of links 60 which are connected at one end with arms 61 from the shafts and with the lower 70 end of a lever 62 which is mounted upon a shaft 63 and extends upwardly above the frame 2 and carries the presser-head 9. The lever is actuated by means of a cam 64 on the shaft 37 which engages with a pin 65 on the lever.

In operating my machine the material is fed to the formers as the wheel is rotated and the bottom is bent into shape by the descent of the presser-head after which the ends are bent in by the pivotal folders and subsequently secured by the stitching mechanism. As 80 the wheel is moved forward step by step and just before each basket reaches the point of ejection the wings that have held it in position are partially opened by the crescent-shaped cam and the bottom of the former is then moved downward and the completed 85 box ejected from the wheel. Immediately thereafter the bottom of the former is automatically returned to its normal position and the wings opened for the reception of the material of a new box. By arranging the formers upon diametrically opposite sides of the wheel the reciprocal frame will normally stand in line with two of them at the same time so that one movement of the frame will complete the folding of the material upon one former and eject the completed box from the other.

By providing the wheel with a sufficient number of 90 formers, six being shown in the drawing, as having been found to be preferable, the machine can be operated very rapidly and an exceedingly large out-put of completed baskets can be secured at a minimum of expense.

Although I have shown what I consider the most desirable form for constructing my machine yet it is evident that changes or alterations may be made in the same and I reserve the right to all such modifications as will come within the scope of my invention.

What I claim and desire to secure by Letters Patent is:

1. In a berry-box machine, a series of intermittently movable formers, means for folding material thereon, an ejector in each former and a reciprocatory frame on, one side of the movable formers for operating the ejectors.
2. In a berry-box machine, a series of intermittently movable formers, means for folding material thereon, an ejector in each former, and reciprocatory means for automatically and positively actuating the ejector.
3. In a berry-box machine, a series of intermittently movable formers, means for folding material thereon, a reciprocatory ejector in each former, and means for simultaneously actuating the ejector and the folding mechanism.
4. In a berry-box machine, a series of intermittently movable formers, means for folding material thereon at one point after it has been fed thereto at another point, stitching the material at another point and ejecting the completed box at another point.
5. In a berry-box machine, an intermittently movable wheel, the periphery of which is provided with a plurality of formers, folders for each former, a presser-head provided with folders, and means for successively bringing the formers under said head and actuating the latter.
6. In a berry-box machine, an intermittently movable wheel, the periphery of which is provided with a plurality of formers, wings pivotally mounted in the wheel at each side of each former, a presser-head provided with folders, and means for actuating said wings after the presser-head has been moved into engagement with the former.

7. In a berry-box machine, an intermittently movable wheel, the periphery of which is provided with a plurality of formers, wings pivotally mounted in the wheel at each side of each former, the wings at one side being wider than those at the other, a presser-head, and means for moving said wings toward the former after said head has been actuated.
8. In a berry-box machine, an intermittently movable wheel, the periphery of which is provided with a plurality of formers, an ejector and folders for each former, a presser-head, and means for actuating the ejector.
9. In a berry box machine, an intermittently movable wheel provided with a plurality of formers, a plate in each former provided with a stem, means for moving said stem 15 and plate downward, a spring for returning them to their normal position, folders for each former, and a presser-head.
10. In a berry-box machine, an intermittently movable wheel provided with a plurality of formers, a plate in the 20 bottom and folders at the sides of each former, a spring and a stem for each plate, means for simultaneously closing the wings upon one former and moving the plate of another former outward, and a presser-head.
11. In a berry-box machine, an intermittently movable 25 wheel comprising two slotted sides, perforated projections on one of the sides, a rod in said perforation provided with a plate at its outer end and a rigid projection at its intermediate portion in position to extend through one of said slots, a spring connected with said plate and the other side of the machine, a head loosely mounted upon said rod and provided with a projection which extends through another of said slots, folders for each former, means for connecting said folders with said head, means for engaging with said projections to actuate the folders and said 30 plate, and a presser-head.
12. In a berry-box machine, an intermittently movable slotted wheel provided with formers arranged diametrically opposite each other folders and an ejector for each former, projections through said slot for actuating the 35 folders and ejectors respectively, a reciprocatory-frame mounted on the axle of the frame of the wheel, each end of which is provided with a lip for engaging the said projections respectively and a presser-head.
13. In a berry-box machine, an intermittently movable 40 slotted wheel provided with formers, folders and an ejector for each former, projections through said slots for actuating the formers and the ejector respectively, a reciprocatory frame provided with means for engaging with said projections, a spring for returning each ejector to its 45 normal position, a crescent-shaped cam for engaging with the projections for actuating the folders and returning them to their normal position, and a presser-head.
14. In berry-box machine, an intermittently movable 50 slotted wheel provided with formers, folders and an ejector for each former, projections through said slots for actuating the folders and ejector respectively, a reciprocatory frame and a cam for engaging with said projections, a lever for actuating said frame, a cam for moving the lever, and a presser-head.
15. In berry-box machine, an intermittently movable 55 slotted wheel provided with formers, folders and an ejector for each folder, projections through said slots for actuating said folders and ejector respectively, a reciprocatory frame and a cam for engaging with said projections, an 60 L-shaped lever connected with said frame, one arm of which is jointed, one member of said arm being extended and yieldingly connected with the other arm, means connected with said extension for adjusting the levers, a cam for actuating the lever and a presser-head.
16. In a berry-box machine, a wheel provided with a 65 plurality of formers, folders and an ejector for each former, means for actuating the same, a presser-head, a disk connected with said wheel, a lock for the wheel, a lever, a 70 push-rod pivotally connected therewith at one end and adapted to release the lock and engage with said recess 75 at the other and give the wheel a partial rotation, and means for actuating the lever and push-rod to carry a former under the presser-head.
17. In a berry-box machine, a wheel provided with a plurality of formers, a presser-head, a disk connected with 80 said wheel and provided with two sets of recesses, a spring pressed lever provided with a pin at one end for engaging with one set of said recesses and having its opposite end standing adjacent to the recess of the other set, a lever, a two-part push-rod connected therewith at one end, a cross 85 bar at the other end of said rod in position for engaging the locking-lever and one of the recesses of the disk and thereby actuating the locking-lever and rotating the disk and wheel whenever said rod is actuated, and a cam for actuating the lever to move the push-rod upward to the 90 limit of its movement prior to the descent of the presser-head.
18. In a berry-box machine, an intermittently movable wheel provided with a plurality of formers, folders and an 95 ejector for each former, a presser-head provided with spring-pressed folders and bottom and means for actuating said head.
19. In a berry-box machine, a wheel provided with a plurality of formers, folders for each former, a lever provided with a perforated head at one end, folders loosely 100 secured at the sides of the head in position to pass down upon the sides of each former, springs for engaging with said folders, bolts through the springs and through the folders into the head, a plate at the lower end of said stem, a spring 105 between the plate and the head, and means for actuating said wheel and lever.
20. In a berry-box machine, an intermittently movable wheel provided with a plurality of formers, folders for 110 each former, a presser-head provided with a yielding bottom, a flat yielding finger projecting beyond each side of said bottom in position for engaging with a piece of material on the former, folders upon said head adapted to bend the ends of said material over the ends of the former, and means for actuating said head and wheel.
21. In a berry box machine, an intermittently movable 115 wheel provided with a plurality of formers, folders for each former, a presser-head above the wheel in position to engage with one of said formers, stitchers upon opposite sides of the wheel adjacent to another former, and means for simultaneously actuating the presser-head and stitchers.
22. In a berry-box machine, an intermittently movable 120 wheel provided with a plurality of formers, folders for each former, a lever, one end of which is provided with a presser-head in position to be moved toward and from one end of said formers, stitchers arranged in duplicate upon each side of the wheel adjacent to another former, a rock-shaft for operating said stitchers, links from said shafts to the other end of said lever, and means for actuating said lever.
23. In a berry-box machine, an intermittently movable 125 wheel provided with a plurality of formers, ribs projecting from oppositely located edges of each former above the bottom, folders for each former, a presser-head provided with means for forcing material between said ribs, and stitching mechanism adapted to engage with material upon said formers.
- In testimony whereof I have hereunto set my name to this specification in the presence of two subscribing witnesses.
